UNITED STATES PATENT OFFICE.

ALONZO TUTTLE, OF BOSTON, MASS., ASSIGNOR TO WILLIAM M. GRISCOM,
MATTHAN HARBSTER, AND WILLIAM HARBSTER, OF READING, PA.

DESIGN FOR SHELF-BRACKETS.

Specification forming part of Design No. 7,366, dated April 14, 1874; application filed February 23, 1874.
[Term of Patent 7 years.]

To all whom it may concern:

Be it known that I, ALONZO TUTTLE, of Boston, Massachusetts, have produced or invented a Design for a Shelf-Bracket, of which the following is a specification:

The figure in the accompanying drawing clearly represents my design for a shelf-bracket. The entire bracket is cast in one piece, the plain portions *a* and *b* adjoining each other at right angles, and being strengthened by a fillet, *d*, within the angle. The ornamental portion of the bracket is connected to the inner sides of the plain portions at the points *e*, and consists mainly of an ornamented ring, *f*, partially surrounded by, and connected to, a scroll-like band, *g*. The ring *f* has an open-scalloped

center, *h*, from which radiate arms *i* crossed by a scalloped band, *k*.

I claim—

The design for a shelf-bracket, consisting of the plain portions *a* and *b*, ornamented ring *f*, and scroll-like band *g*, all as described, and as represented in and by the accompanying drawing.

In testimony whereof I have signed my name to this specification in the presence of two subscribing witnesses.

ALONZO TUTTLE.

Witnesses:

WILLIAM CALDWELL,
CHAS. HALL ADAMS.
